UNITED STATES PATENT OFFICE.

FRANK KUSTERLE, OF KENOSHA, WISCONSIN, ASSIGNOR TO SIMMONS COMPANY, OF KENOSHA, WISCONSIN, A CORPORATION OF DELAWARE.

DISPLAY-RAIL.

1,278,942.

Specification of Letters Patent. Patented Sept. 17, 1918.

Application filed March 4, 1918. Serial No. 220,398.

To all whom it may concern:

Be it known that I, FRANK KUSTERLE, a citizen of the United States, residing at Kenosha, in the county of Kenosha and State of Wisconsin, have invented certain new and useful Improvements in Display-Rails, of which the following is a specification:

My invention relates to improvements in display rails, that is to say, a short rail or connection which is employed as a substitute for the side rail of a bedstead when the latter is on display as a sale sample. Inasmuch as an ordinary bed rail is about six feet in length it is usually impracticable on account of limited space to set up a bedstead complete with its side rails. Since it may be necessary to display a large number of different types of bedsteads on the same floor, in order to overcome this difficulty what is called a "short" rail or a display rail is employed to connect temporarily the foot and head ends of the bedstead while on display, this short rail being usually from one to four inches in length instead of six feet as in the case of the ordinary side rail.

I am aware that short rails have been employed heretofore but such devices as have been up to the present brought to my attention are either more or less makeshift in character or they are subject to mechanical defects such for instance as not maintaining the two parts of the bedstead in vertical and parallel relation.

The principal objects of the present invention are to provide an improved short rail construction which may be made up in large quantities rapidly and economically; to provide an improved short rail by means of which the two parts of the bedstead may be rigidly and, if desired, permanently, secured together; to provide an improved construction which shall permit of the foot and head ends of the bedstead being handled as a single unit without danger of their becoming separated or divorced from each other; to provide an improved construction which shall maintain the said parts rigidly in parallel and vertical relation; to provide a device which may be applied or detached quickly and conveniently without the necessity of employing tools or other extraneous devices, and in general, to provide a neat simple and economical construction of the character referred to.

In the drawings which illustrate a specific embodiment of my invention as applied to the foot and head ends of a round post metal bedstead, Figure 1 is an elevation of the two parts of the bedstead connected together by means of my improved device;

Fig. 2 is an enlarged sectional view of the parts of the device shown in Fig. 1;

Fig. 3 is an end view of the device before it is applied to the bedstead, and

Fig. 4 is a section taken on the line 4—4 of Fig. 2.

Referring to the drawings, 10 and 11 represent the head and foot ends of a metal bedstead of the round post type which is to be displayed on the sale floor. It will be observed that the said two parts are placed relatively close together so as to economize space, the short rail designated as a whole 12 in Fig. 1 connecting the ends together at a sufficient distance apart to prevent them from being accidentally overturned while being moved around on the sale floor.

The short rail 12 is constructed as to its principal parts of inexpensive sheet iron or steel stampings, said stampings comprising a pair of U-shaped pieces 13 and 14, a washer plate 15 and a key member or wedge plate 16. The bottom U-shaped plate 13 is united to the top plate 14 by spot welding as shown best at 17 in Fig. 2, and it will be observed that the bottom U-shaped member 13 is of substantially rectangular box shape so that it is adapted to fit snugly between the opposed faces 18 and 19 of the bedstead corner connections 20 and 21.

The upper or top plate 14 is of greater length than the distance between the corner connections 20 and 21 so that there are provided a pair of over-hanging portions 22 and 23 which project over and rest upon the tops of the said parts 20 and 21.

In the present instance I have shown my invention as applied to a bedstead employing what are known in the bedstead art as frenchings; these being cast iron corner blocks secured to the end of the bedstead and being suitably arranged to detachably interlock with parts carried by the ends of the side rails. In the drawings I have shown these frenchings as being of the usual dovetail type having the customary taper openings 24 and 25 with which the male parts of the side rails are wedgingly engaged.

The female dovetail openings in the op-

posite faces of the frenchings 20 and 21 of the bed ends, are taken advantage of by me in order to secure a rigid connection between the said frenchings. To this end I employ 5 the vertically adjustable key plate, or wedging member 16, the opposite ends of which are formed with circular lugs 26 and 27 which are arranged to have wedging engagement with the said female dovetail openings 24 and 25. It will be manifest that 10 when the key plate 16 is moved downwardly the projections 26 and 27 will wedgingly engage the dovetail openings 24 and 25 and cause the frenchings 20 and 21 to be drawn 15 together into tight fitting engagement with the opposite edges of the box-shaped stamping 13. Such downward adjustment to the key plate 16 is effected by means of a screw 28 which is threaded into the key plate 16 as 20 shown at 29 and for additional security the head of the said screw may be riveted over as shown at 30. Also if desired a lock nut 31 may be threaded on to the screw underneath the key plate. In order to prevent 25 the key plate from having excessive side play a pair of lugs 32 and 33 are spaced apart a sufficient distance to fit loosely between the vertical parts of the box shaped stamping 13.

30 Threaded on the lower end of the adjusting screw 28 is a nut 34 which co-operates with the washer plate 15 to pull the key plate 16 downwardly into tight fitting engagement with the dovetail openings 24 and 35 25 in the drawings. It is manifest that the washer plate 15 must be of sufficient length to bridge the bottoms of the frenchings 20 and 21 and in order to facilitate the application of the device, the said washer plate 15 40 is preferably made of less width than the box-shaped member 13 so that by turning the plate 15 through an angle of 90 degrees, the device may be lowered into position with the key plate 16 in dovetail engagement with 45 the frenchings. After the device has been lowered the member 15 is then turned through an angle of 90 degrees so as to cause the ends of the washer to engage under the frenchings after which the nut 34 is 50 tightened up thereby pulling the key plate downwardly and clamping the various parts rigidly and securely together.

55 It will be apparent that by reason of the wedging engagement between the key plate 16 and the frenchings, the latter two parts are forced strongly toward each other and hence tightly engage the edges of the box-shaped plate 13 both the top and the bottom of the latter thus causing the faces of the 60 frenchings 20 and 21 to assume a parallel relation thereby holding the foot and head

ends of the bedsteads vertical. To allow for possible irregularities in the facing of the frenchings the vertical edges of the box-shaped stamping 13 are cut away slightly as 65 shown at 35 (see Fig. 2).

Inasmuch as the details of construction may be varied considerably without sacrifice of efficiency, it may be well to state that the 70 said details as above described are intended to be merely illustrative of a single application of my invention, the scope of which should be determined by reference to the appended claims.

75 I claim—

1. A short rail of the class described comprising a box shaped metal spacing member and a member slidably mounted with reference to said spacing member and having opposite ends wedgingly engaging the bed parts to be connected for drawing the same into tight fitting engagement with the said spacing member.

80 2. A short rail of the class described comprising a box shaped metal spacing member, a member slidably mounted with reference to said spacing member and having opposite ends wedgingly engaging the bed parts to be connected for drawing the same into tight 85 fitting engagement with the said spacing member, and means for moving said wedge member downwardly.

90 3. A short rail of the class described comprising a spacing member substantially rectangular in elevation, disposed between the opposed parts of two bed parts to be temporarily connected, a horizontal plate slidably arranged within said spacing member and having at each of its opposite ends a 95 part wedgingly engaging one of the bedstead parts and a screw for moving the said plate downwardly into wedging engagement with the said bed parts to cause the latter to forcibly engage the rectangular 100 spacing member.

105 4. A short rail of the class described for connecting bed parts having opposed similar female dovetail openings which comprises a rectangular stamped hollow spacing member rectangular in elevation for fitting between opposed faces of said dovetail parts, a plate slidably contained within said hollow spacing member and having at its end a projection arranged to wedgingly engage 110 one of the said dovetail openings in said bedstead parts, a vertical screw having its upper end connected to the said plate and provided with a nut on its lower end and a washer interposed between said nut and the 115 said spacing member for engaging bottom faces of said dovetail parts.

120 FRANK KUSTERLE.
